UNITED STATES PATENT OFFICE.

WILLIAM H. PHENICE, DECEASED, BY ESTHER A. PHENICE, EXECUTRIX, OF WHITE HALL, ILLINOIS.

KITCHEN-CABINET.

1,204,059.

Specification of Letters Patent. Patented Nov. 7, 1916.

Application filed November 16, 1915. Serial No. 61,861.

To all whom it may concern:

Be it known that WILLIAM H. PHENICE, deceased, late a citizen of the United States, did invent certain new and useful Improvements in Kitchen-Cabinets, of which the following is a specification.

The present invention relates in general to furniture and more particularly to improvements in the kitchen cabinet for which 10 Letters Patent No. 522,485 were issued July 3, 1894.

Among the objects of the invention is the provision of novel means for mounting revolving shelves in a cabinet of this character whereby the same are always held in a horizontal position and can be brought successively to the front of the cabinet.

For a full description of the invention and the merits thereof and also to acquire 20 a knowledge of the details of construction and the means for effecting the result, reference is to be had to the following description and accompanying drawings, in which:

Figure 1 is a perspective view of a kitchen cabinet constructed in accordance with the invention. Fig. 2 is a longitudinal sectional view through the rear portion of the cabinet, the upper portion thereof being removed. Fig. 3 is a transverse section 30 through the cabinet. Fig. 4 is a front view of the top of the cabinet, parts being broken away. Fig. 5 is a detail view of the guide ring.

The cabinet embodies a lower casing 1 and an upper casing 2, the latter resting upon the former and in the present instance being shown as formed separate and detachably secured to the lower casing by the hook members 3. A plurality of shelves 4, arranged in the lower casing are normally closed by doors 5 located at the front of the casing and hinged at opposite ends thereof. A vertical recess 6 is formed between the doors 5 for receiving the legs 7 utilized for supporting the sliding shelf 8 when the latter is withdrawn beyond the cabinet. The upper ends of these legs 7 are connected to arms 9 which are pivoted to the casing at points toward the ends thereof. A pair of link members 11 form operative connections between the sliding shelf 8 and the legs 7 whereby the latter are simultaneously swung outwardly when the sliding shelf is withdrawn, and moved back as the shelf is housed. A cleat 12 is located at each end

of the sliding shelf 8 in substantially the same horizontal plane with the arms 9 so as to limit the movement of the parts.

A drawer 13 is located at each end of the lower casing and a flour chest 14 is received within the space back of the shelves 4. Guide bars 15 extend from opposite sides of the flour chest while the outer portion of the chest is supported by rollers 16. The flour chest is subdivided by a transverse 65 partition 17 and a removable drawer 18 is located immediately below the sifting screen 19 at the bottom of the outer compartment and over which is an agitator 20 having an operating handle 21. A cover 22 is provided for the flour chest.

A number of transverse shelves 23 are located in the rear portion of the lower casing 1 at the end thereof opposite that within which the flour chest is mounted, and the 75 said shelves are normally closed by a swinging door 24.

The upper casing 2 rests upon the lower casing 1 and is provided at its forward and rear portions with the removable closures 27 which project outwardly beyond the sides of the casing to form a clearance space for the revolving shelves 28. These closures 27 are provided at their opposite ends with flanges 29 received between the sides of the upper casing and detachably connected thereto by screws or other suitable fastening members. The closure 27 at the front of the upper casing is also provided with a downwardly swinging door 30 adapted to uncover an opening through which access can be had to the various shelves 28 as the same are successively brought to the front of the casing. Journaled in and extending between the opposite ends of the upper casing 2 is a shaft 31, the extremities of which are detachably engaged by screws or pins 32 extending through the casing, whereby when the said pins are removed the shaft is released and can be taken out of the cabinet. Carried by each end of the shaft 31 is a head 33 to which upright hangers 34 at opposite ends of the shelves 28 are pivoted, the said hangers being rigid with the shelves so that the latter assume a horizontal position when the former are vertical.

For the purpose of preventing swinging movement of the hangers 34 such as would tilt the shelves 28 and move the same out of a horizontal position a plate is located adja-

80

cent one of the heads 33, the said plate being pivotally connected to the shelves and the edges of the plate being engaged by guides 35 whereby the same is held against lateral displacement. In the preferred construction this plate is in the nature of a ring 36, various points in the periphery of which are pivotally connected to the respective shelves, the said ring being arranged eccentrically with regard to the head 33 and the outer edge of the ring being received loosely between spaced fingers 37 upon the guides 35 at the front and rear of the cabinet. One of the heads 33 engages a belt or chain 38 which also passes around a wheel 39 mounted upon one end of the upper casing toward the front thereof, the said wheel being designed to be operated by a crank handle 40 upon the exterior of the cabinet. By turning this handle 40 motion is transmitted to the heads 33 through the medium of the belt 38 and the various shelves 28 can be moved and brought successively to the front of the casing, the ring 36 coöperating with the hangers to maintain the shelves always in a horizontal position. For the purpose of locking the shelves 28 against movement should the weights thereon be unevenly distributed a detent 41 is provided, the said 30 detent being shown as mounted upon the closure 27 at the front of the cabinet and as designed to engage the belt or chain 38. This detent is manipulated through the medium of a handle or finger piece 42 projecting through the front of the casing.

Located under the revolving shelves 28 and toward the rear portion of the upper casing 2 is a pair of drawers 43 removable through the ends of the cabinet and formed of sheet metal so as to receive ice for preserving and cooling the provisions upon the revolving shelves. These drawers 43 are perforated and are disposed over a metallic tray 44 provided at the rear portion thereof with a discharge opening 45. If found desirable openings 46 may be formed at various points in the cabinet for the purpose of obtaining ventilation, the said openings being covered with screening and provided 50 with sliding doors as shown. A plurality of compartments are formed in the forward portion of the upper casing 2 below the removable closure 27, and the said compart-

ments are designed to receive the removable bins 47, the upper portions of the bins being 55 closed by the hinged doors 48.

It will be observed that the top of the upper casing is inclined at the front and rear thereof, and it is contemplated to provide this inclined portion at the front of 60 the casing with brackets 49 supporting shelves 50 which may receive plates or other articles as found desirable.

Having thus described the invention, what is claimed as new is:

1. In a cabinet of the character described, the combination of a casing, a shaft journaled within the casing, heads carried by the shaft, revolving shelves provided at their ends with hangers engaging the heads, 70 a ring loosely engaging the shelves to retain the same in a horizontal position, guides for the ring, and means for rotating the shaft.

2. In a cabinet of the character described, 75 the combination of a casing, a shaft journaled within the casing, heads carried by the shaft, revolving shelves provided with hangers loosely connected to the heads, a ring loosely connected to the shelves for 80 holding the same in a horizontal position, a wheel mounted upon the casing, a belt for transmitting motion from the wheel to one of the heads, and means for turning the wheel.

3. In a cabinet of the character described, the combination of a casing, a shaft journaled within the casing, a head mounted upon each end of the shaft, revolving shelves mounted between the heads and provided at their ends with hangers pivotally connected to the heads, a ring having various points in the periphery thereof pivotally connected to the shelves, guide members mounted upon the casing and engaging the ring to cause the latter to hold the shelves in a horizontal position, a wheel journaled upon the casing, a belt for transmitting motion from the wheel to the shaft, and means for turning the wheel.

In testimony whereof, I affix my signature.

ESTHER A. PHENICE, [L. s.]
Executrix of last will and testament of William H. Phenice, deceased.
